MOUTH-PROTECTING DEVICE

Hans P. Lee, Toledo, Ohio

Application November 2, 1950, Serial No. 193,569

6 Claims. (Cl. 128—136)

1

This invention relates to a mouth-protecting device for insertion in a patient's mouth to protect his or her teeth, tongue and lips during convulsions, such as for example those created by electric-shock treatments.

Previously, during such treatments towels or pads of gauze have been inserted in such patients' mouths, but these do not always afford sufficient protection from bite injury and often impede respiration. Furthermore, such an insert or mouth prop may be chewed to bits during the convulsion.

It is an object of this invention to provide a new, simple, effective, efficient, comfortable and economical mouth-protecting device for use during convulsions, which has the following advantages:

- a. It pushes the tongue back away from the teeth, thus preventing it from being injured by biting.
- b. It pushes the lips and cheeks away from the teeth, again preventing injury by biting.
- c. It provides means whereby the force of the biting action on the part of the patient can be applied at the most desirable points bilaterally between the jaws, thus protecting the weaker teeth, and preventing dislocation of the jaw.
- d. It provides an airway for respiration through the mouth.
- e. It can be sterilized by boiling or immersing in disinfectants and thereby can be used a great many times.

In accordance with this invention, the mouth-protecting device is composed of a semi-resilient material, such as for example rubber, and has the general overall configuration of a wedged-shaped annulus or ring with a pair of protuberances on opposite sides of the ring to be used as handles. The portion of the device having the handles may be relatively straight while the remaining portion of the device may be considered to form an arcuate bow between the ends of the straight handle portion, thereby providing the hole of the ring between said arcuate portion and said straight handle portion. The arcuate portion is the portion which is for insertion into the patient's mouth.

The above mentioned and other features and objects of this invention and the manner of attaining them are given more specific disclosure by reference to the following description of an embodiment of the invention taken in conjunction with the accompanying drawings, wherein:

2

Fig. 1 is a plan view of one form of the mouth-protecting device;

Fig. 2 is a section along line II—II of the device in Fig. 1;

Fig. 3 is a manually deformed plan view of the device in Fig. 1 on a slightly reduced scale; and

Fig. 4 is a side view on a slightly reduced scale of the device of Fig. 1 shown in position in a patient's mouth.

Referring to the drawings, the device comprises a relatively straight bar or handle portion 10 and an arcuate bowed or mouth-insertable portion 20. The handle portion has a rectangular cross-section 11 (see Fig. 2), with normally flat parallel ends 12 and 13, flat parallel top and bottom faces 14 and 15, between which is the major thickness of the device, and concave outer and inner sides 16 and 17, respectively, the former or outer side 16 having herein a normal curvature of at least the length of the handle portion from ends 12 to 13, and the latter or inner side 17 normally having the curvature of a central hole 18 of lesser diameter than said handle length.

The mouth insertable portion 20 may be considered to bow between the ends of the handle portion 10 forming an arcuate portion which merges into the parallel outer end surfaces 12 and 13 on the outside at regions 22 and 23 and with the inner curvature 17 forming the hole 18, which overall configuration produces the device's general annular or ring shape. The mouth insertable portion 20 has less thickness throughout than that of the major thickness of the handle portion 10 by being offset from the top and bottom faces 14 and 15 along the rounded edges 22 and 23. From these regions or offsets 22 and 23 the arcuate portion 20 tapers slightly together so that the part most remote from the handle portion 10 has the least thickness as well as the least width of any part of the device, as indicated by a cross-section region 24 in Fig. 2.

In other words, the whole configuration of the device could also be considered to be a wedge shaped annulus or ring with handle protuberances terminating at the end surfaces 12 and 13.

If desired, the device may be deformed to fit wider mouths by squeezing the ends 12 and 13 together between one's thumb 41 and forefinger knuckle 42, as shown in Fig. 3, so that the device can be gripped by the teeth of any patient at the desirable bilateral points between the jaws, i.e. where about the first molars on each side of a patient's mouth grip the device across the arcuate portion 20 in regions 25 and 26.

The thinnest and narrowest part or region 24 holds a tongue 30 (see Fig. 4) of a patient in place, and the hole 18 spaces weaker front teeth 31 and 32 and prevents them from grinding against each other during the convulsion. Thus, when the device is properly in place in the patient's mouth, lips 33 and 34 of the patient will just touch the offsets 22 and 23 as shown in Fig. 4.

While there is described above the principles of this invention in connection with a specific embodiment thereof, it is to be clearly understood that this description is made only by way of example, and that other devices performing the same function, but of slightly different outside curvature and design, can be made without departing from the scope of this invention. Accordingly, the present disclosure is not to be considered as a limitation to the scope of this invention.

What is claimed is:

1. A mouth-protecting device composed of a resilient material and having an annular type configuration with a central hole, said configuration comprising: a thicker front handle portion, a thinner arcuate mouth insertable back portion, and two curved side parts connecting and merging into the ends of said two portions to provide said hole, said side parts and said arcuate portion tapering in thickness away from said handle portion.

2. A device according to claim 1, wherein said handle portion has opposite normally parallel flat sides and ends and a concave outer face opposite said hole.

3. A device according to claim 1 composed of rubber.

4. A device according to claim 1 wherein said two curved side parts and said arcuate portion taper toward reduced width as well as thickness to a point farthest away from said handle portion.

5. A mouth-protecting device composed of a resilient material and comprising: a bar portion having a substantially rectangular cross-section providing a handle outside the mouth, and an arcuate portion bowed between the ends of said bar portion thinner than said portion and tapering both in thickness and width away from said bar portion to a thinnest and narrowest part thereof on said arcuate portion most remote from said bar portion, said arcuate portion being insertable in the mouth for being gripped between the teeth, and said arcuate portion providing a normally circular hole through the thickness of said device.

6. A device according to claim 5 wherein said bar portion has a concave outer surface opposite the side of said hole.
